(57) **CLAIM**

The ornamental design for a bracket, as shown and described.

DESCRIPTION

FIG. 1 is a front perspective view of a bracket showing my new design;

FIG. 2 is a top view of the design shown in FIG. 1;

FIG. 3 is a right side view of the design shown in FIG. 1 (the other side is a mirror image);

FIG. 4 is an end view of the design shown in FIG. 1 looking forward from the small end;

FIG. 5 is an opposite end view; and,

FIG. 6 is a top perspective view of the design shown in FIG. 1 in use condition having a camera attached at one end of the bracket.

The broken line showing of a camera is included for the purpose of illustrating environmental structure only and forms no part of the claimed design.
